UNITED STATES PATENT OFFICE.

PETER BARTZEN, OF HURON, OHIO.

TRACE-HOOK.

SPECIFICATION forming part of Letters Patent No. 424,950, dated April 8, 1890.

Application filed February 21, 1890. Serial No. 341,297. (No model.)

To all whom it may concern:

Be it known that I, PETER BARTZEN, a citizen of the United States, residing at Huron, in the county of Erie and State of Ohio, have 5 invented a new and useful Trace-Hook, of which the following is a specification.

The invention relates to improvements in trace-hooks.

The object of the present invention is to 10 provide a simple and inexpensive trace-hook adapted to be readily secured to a whiffletree of the ordinary construction and capable of enabling a heavy load to be gradually started without jars to the animal and to prevent jars 15 during the passage of the vehicle over rough surfaces.

The invention consists in the construction and novel combination and arrangement of parts hereinafter fully described, illustrated 20 in the accompanying drawings, and pointed out in the claims hereto appended.

In the drawings, Figure 1 is a perspective view of a whiffletree provided with a trace-hook constructed in accordance with the invention. Fig. 2 is a detail view of the hook 25 detached. Fig. 3 is a similar view of the T-shaped plate. Fig. 4 is a plan view of one end of the whiffletree, showing how the spring trace-hook is pulled forward by the draft.

Referring to the accompanying drawings, 30 1 designates a whiffletree which is provided near its end with a T-shaped plate 2, that is constructed of metal, and is secured to the rear face of the whiffletree, and has its arm 3 35 perforated and secured to the whiffletree by a screw 4, and the arms 5 and 6, arranged at right angles to the arm 3, rounded and adapted to receive coils or eyes 7, that are formed in a whiffletree-hook 8. The whiffletree-hook is 40 constructed of a single piece of spring-wire that is doubled and formed approximately U-shaped to enable it to fit around a whiffletree, and has its sides 9 bent at right angles and provided at the bends with eyes 7, that 45 are formed by coiling the wire. The extreme

ends of the wire forming the trace-hook are twisted and bent into the form of a hook and adapted to readily be connected to the end of a trace. By this construction as soon as an animal attempts to start a loaded vehicle his 50 force will first be exerted against the spring of the trace-hook and then upon the load, by which means any sudden jars in starting heavy loads are prevented, and jars are also prevented while the vehicle is passing over 55 uneven surfaces.

From the foregoing description and the accompanying drawings the construction, operation, and advantages of the invention will 60 readily be understood.

What I claim is—

1. A trace-hook adapted to be pivoted to a whiffletree and constructed of a single piece of spring-wire doubled and embracing the whiffletree at the end, and having its sides 65 bent approximately at right angles and the ends of the wire formed into a hook, said sides being provided at their bends with coils forming eyes by which the hook is pivoted, substantially as and for the purpose described. 70

2. The combination of the T-shaped plate, adapted to be secured to a whiffletree, and having its arms 5 and 6 arranged to project beyond the whiffletree and being rounded, and the trace-hook constructed of a single 75 piece of spring-wire doubled, and having its sides bent at an angle and its ends twisted and formed into a hook, said sides being provided at their bends with coils forming eyes adapted to receive the rounded arms of the 80 T-shaped plate, substantially as and for the purpose described.

In testimony that I claim the foregoing as my own I have hereto affixed my signature in presence of two witnesses.

PETER BARTZEN.
